(57) **CLAIM**

The ornamental design for a baby cushion, as shown and described.

DESCRIPTION

FIG. 1 is a top, front and left side perspective view of a baby cushion showing the new design;

FIG. 2 is a bottom, rear and right side perspective view thereof;

FIG. 3 is a front view thereof;

FIG. 4 is a rear view thereof;

FIG. 5 is a top view thereof;

FIG. 6 is a left side view thereof;

FIG. 7 is a right side view thereof;

FIG. 8 is a bottom view thereof;

FIG. 9 is a right side view of the baby cushion in a collapsed condition;

FIG. 10 is a top view thereof;

FIG. 11 is rear view thereof; and,

FIG. 12 is a front view thereof.

The broken line showing of the inflation valve in FIGS. 2, 4, and 5–11 is for illustrative purposes only and forms no part of the claimed design.

1 Claim, 4 Drawing Sheets
